UNITED STATES PATENT OFFICE.

JOHN Z. MILLER, OF ERIE, PENNSYLVANIA.

TELEPHONE-TRANSMITTER.

No. 809,831.

Specification of Letters Patent.

Patented Jan. 9, 1906.

Application filed October 19, 1904. Serial No. 229,171.

To all whom it may concern:

Be it known that I, JOHN Z. MILLER, a citizen of the United States, residing at Erie, in the county of Erie and State of Pennsylvania, have invented new and useful Improvements in Telephone-Transmitters, of which the following is a specification.

This invention relates to telephone-transmitters; and it consists in certain improvements in the construction thereof, as will be hereinafter fully described, and pointed out in the claims.

The invention is illustrated in the accompanying drawings, as follows:

15 Figure 1 is an elevation of the mouthpiece; Fig. 2, a section on the line 2 2 in Fig. 3; Fig. 3, a view from the bottom of Fig. 2; Fig. 4, an elevation of the shell for the back of the case.

20 The transmitter is mounted in the case A, which has the screw-threads *a* for receiving the mouthpiece D. A back plate B, preferably formed of rigid conducting material, is secured to the case by the screws C. The 25 washer E, formed of a fabric, preferably felt, is arranged on the back plate B. The electrode F is placed within the washer E in contact with the plate B. A granulated conducting material G is placed in the space 30 above the electrode F, so as to form a variable conductor on which the diaphragm H may act. I preferably interpose a second electrode F', which is mounted on the diaphragm H and extends into the cavity in the washer. The diaphragm H extends over 35 and closes the cavity in the washer, it being mounted in contact with the washer and in position to contact the granulated conducting material G. The diaphragm is mounted 40 on a ring H', formed of conducting material and insulated from the case and back plate by insulating-rings *h*, *h'*, and *h''*. A conductor I leads from the ring through an opening *b* in the back plate to a terminal J, the terminal 45 being mounted on the insulating-block *j*. The block *j* is mounted on the back plate. The back of the transmitter proper is inclosed by a shell K, which is secured to the case by the screws *k*. The shell is of such diameter 50 and shape as to fit the outer wall *a'* of the case. By this construction the essential parts of the transmitter are entirely inclosed and practically moisture-proof, thus assuring durability and uniformity of operation. This

is accomplished by making the rings *h* and *h'* 55 of a comparatively soft insulating material, so as to seal the transmitter against any moisture that may enter through the mouthpiece. The washer E forms a damper which modulates the vibrations of the diaphragm, 60 thus giving a more accurate reproduction of the sounds transmitted. The comparatively rigid back plate in connection with the granulated material gives uniformity of microphone effect. 65

What I claim as new is—

1. In a telephone-transmitter, the combination of a non-vibrating back plate; a washer of fibrous and non-conducting material forming a container; and dampener mounted on 70 the back plate; an electrode arranged within the washer, the electrode being of less thickness than the washer; granulated conducting material in the cavity with the electrode; a ring of conducting material arranged outside of said washer and mounted within the case but insulated from the case and back plate; and a diaphragm mounted on said ring and in electric contact with said ring and being connected with the back plate through the 75 electrode and material in the cavity and the washer.

2. In a telephone-transmitter, the combination of the case A having a cavity therein for containing the transmitting parts; a non-vibrating back plate secured to the case and closing said cavity; a fibrous washer mounted on the back plate; transmitting material arranged in the washer; the diaphragm H arranged over the washer and in contact with 80 the transmitting material; the ring *H'* on which the diaphragm is arranged; the packing-rings *h* and *h'* for sealing the space between the diaphragm and the back plate, and for insulating the diaphragm from the back plate 85 and case; the terminal *J*; and means for connecting said terminal with the diaphragm.

3. In a telephone-transmitter, the combination of the case A having a cavity therein for containing the transmitting parts; a non-vibrating back plate secured to the case and closing said cavity; a fibrous washer mounted on the back plate; transmitting material arranged in the washer; the diaphragm H arranged over the washer and in contact with 90 the transmitting material; the ring *H'* on which the diaphragm is arranged; the packing-rings *h* and *h'* for sealing the space between the diaphragm and the back plate, and for insulating the diaphragm from the back plate 95 and case; the terminal *J*; and means for connecting said terminal with the diaphragm. 100

tween the diaphragm and the back plate, and
for insulating the diaphragm from the back
plate and case; the terminal J; means for con-
necting said terminal with the diaphragm;
5 and the shell K secured to the back of the
case and inclosing the plate.

In testimony whereof I have hereunto set

my hand in the presence of two subscribing
witnesses.

JOHN Z. MILLER.
